CONTAINER

**Brown Bolté and Robert R. Dixon,
New Canaan, Conn.**

Application March 9, 1948, Serial No. 144,998

Term of patent 7 years

(Cl. D58—12.6)

To all whom it may concern:

Be it known that we, Brown Bolté and Robert R. Dixon, both citizens of the United States of America and residents of New Canaan, in the county of Fairfield and State of Connecticut, have invented a new, original, and ornamental Design for Container, of which the following is a specification, reference being had to the accompanying drawing, forming part hereof, in which—

Fig. 1 is a side elevational view of a container, showing our new design.

Fig. 2 is a top plan view thereof.

Fig. 3 is a fragmentary cross sectional view taken on the line 3—3 of Fig. 1.

We claim:

The ornamental design for a container, as shown.

**BROWN BOLTÉ.
ROBERT R. DIXON.**
